UNITED STATES PATENT OFFICE.

ELERIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

PNEUMATIC WEFT DETECTOR FOR LOOMS.

Application filed August 29, 1925. Serial No. 53,345.

This invention relates to weft detectors for weft replenishing looms and it is the general object of the invention to provide a detector having a soft yieldable portion 5 to engage the yarn so constructed as not to abrade the yarn.

In the weaving of very fine yarn such as silk a bobbin may remain in action long enough to cause objectionable wearing of 10 the yarn when the usual form of detector is used. In order to reduce the impact between the yarn and the detector I make the latter of a yielding material such as rubber and depend for its operation upon 15 the ability of the detected surface to allow air to pass therethrough.

It is a further object of my invention to provide a detector to engage the yarn of the bobbin and operable to give an indication 20 of weft exhaustion upon a marked reduction in the permeability of the detected surface to the passage of air.

With these and other objects in view 25 which will appear as the description proceeds my invention resides in the combination and arrangement of parts hereinafter described and set forth in the claims.

In the accompanying drawings wherein 30 a convenient embodiment of my invention is shown,

Fig. 1 is a top plan view of my detector, parts of the same being shown in section and the detector being in position to indicate substantial exhaustion of filling,

Fig. 2 is a view similar to Fig. 1 but showing the detector in non-indicating position,

Fig. 3 is a vertical section on line 3-3 of Fig. 1,

Fig. 4 is a perspective view of the yarn engaging tip for the feeler, and

Fig. 5 is a reduced vertical section on line 5-5 of Fig. 1.

In carrying out my invention I provide 45 a detector stand 10 having an upstanding arm 11 provided with a slot 12 disposed vertically in the arm 11 to receive a lever 13 mounted for reciprocation therein. A controller pin 14 passes through the rear portion of the arm 11 and is provided with a piston 15 fitted snugly in a bore 16 formed in the arm 11. A light spring 17 is interposed between the arm 11 and the piston and

acts normally to move the controller pin 14 55 from under the lever 13. When said lever is free to move downwardly no indication is given but when the controller pin 14 is moved thereunder said pin becomes a rolling pivot for the lever and the motion of the 60 latter is altered in such a way as to effect indication of weft exhaustion. The manner in which said lever operates to set the replenishing mechanism is set forth in 65 Patent No. 1,030,748 to which reference may be had for a further description thereof.

Projecting upwardly from the stand 10 and spaced from the arm 11 is a second arm 18 (see Fig. 5) to which is secured a screw 19. A feeler bed 20 has depending therefrom a lug 21 which has pivotal connection with the screw 19, the latter being turned to move the feeler bed toward or from the arm 11. A cap 22 is secured to the bed 20 and defines with the latter a cylinder 23. 70 A pipe 24 threaded into the forward end of the bed and the cap is connected to one end of a rubber tube 25 the other end of which is connected to a second pipe 26 soldered or otherwise secured to a threaded nipple 27. By means of the matter thus far described compression of air in the cylinder 23 will move the controller 14 under the lever 13.

Compression of air in said cylinder 23 is 75 accomplished by means of a plunger 28 which fits snugly in said cylinder and extends rearwardly beyond the end of the cap and bed 22 and 20 respectively. As shown 80 in Fig. 3 the rear end of said plunger is flattened as at 29 and has tightly fitted thereover a flexible collar or sleeve 30 formed preferably of soft rubber. An air passage 31 extends through the plunger 28 and connects the cylinder 23 with the atmosphere. An arm 32 projects laterally from the plunger 28 and has extending therethrough a 85 guide pin 33 around which is disposed a coil spring 34. The latter extends between the arm 32 and a boss 35 formed on the bed to which the pin is secured and serves normally to hold the plunger against adjusting set nuts 36 threaded on the rod 33. Adjustment of said nuts 36 determines the limit 90 of movement rearwardly of said plunger 28 under influence of the spring 34. The collar 30 is preferably of the form shown in 95

Fig. 4 having a narrow orifice positioned to engage the surface of the bobbin.

Under normal conditions when there is sufficient yarn for continued weaving as indicated in Fig. 2 the collar will engage the weft of the bobbin to form an air chamber therewith and as the shuttle moves forwardly the plunger 28 will be moved to compress the air in cylinder 23. Because of the amount 10 of yarn present the compressed air will be able to escape between the coils of yarn on the bobbin. Plunger 15 will therefore remain in normal position to keep the controller pin 14 out of the path of the lever 13. 15 As the layer of yarn becomes thinner more resistance is offered to the passage of air through the yarn and when the yarn is substantially exhausted as indicated in Fig. 1 the air will not be able to escape as fast as 20 it is compressed and will move the piston 15 and place the controller 14 under the lever 13. This condition, as previously described, is attended by a change in the operation of 25 the loom. As the lay recedes the bobbin will move away from the collar 30 to establish connection between the cylinder 23 and the atmosphere, after which the spring 17 will restore controller 14 to its normal forward position out of the path of the lever 13. 30 From the foregoing it will be seen that I have provided a weft detector having a yarn engaging tip formed of easily compressed material such as soft rubber and that at substantial exhaustion of weft said tip forms an 35 air tight connection with the bobbin to prevent the escape of air which is compressed as the advancing lay moves the plunger 28 forwardly. The air passes through the coils of yarn without injury to the same and there 40 is substantially no change in the behavior of the flexible collar 30 as exhaustion of yarn approaches.

Having thus described my invention, it will be apparent that changes and modifications 45 may be made therein by those skilled in the art without departing from the spirit and scope of the invention, and I do not wish to be limited to the details herein disclosed, but what I claim is:

50 1. In a weft detector for looms, a surface to be detected, a member deformable to the shape of the surface to be detected and having an opening therein for the passage of air, and means pneumatically connected with 55 the opening in the member to prevent the indication of weft exhaustion when air can pass from the member through the surface to be detected and effective to indicate exhaustion when air cannot pass from the 60 member through the surface to be detected.

65 2. In a weft detector for the bobbins of looms, an air cylinder, a plunger having a portion thereof movable in said cylinder, a hollow yieldable member mounted on said plunger to engage the surface of the bobbin

to be detected and deformable to the shape of said detected surface to form with the latter an air chamber, said plunger having a passage therethrough to connect the cylinder with the air chamber, and means to indicate substantial exhaustion of weft operable when said plunger compresses air in the cylinder and the air is prevented from passing from the air chamber through the detected surface. 75

3. In a weft detector for looms, a cylinder, a plunger mounted substantially air-tight therein, a yieldable member mounted on the plunger in position to be engaged by the surface to be detected, said member forming 80 with the detected surface and adjacent portions of the plunger an air chamber, a second cylinder, a piston mounted in said second cylinder, and means under control of the piston to indicate substantial exhaustion of weft, 85 said plunger having an air passage therethrough communicating with the air chamber and the cylinder, and said cylinders being pneumatically connected together.

4. In a pneumatic weft detector for the 90 bobbin of a loom, means defining an air chamber, a piston movable in the air chamber, means to indicate weft exhaustion connected pneumatically with the air chamber and operable when air is compressed in the 95 chamber, and a deformable member carried by the piston and engaging the bobbin, said piston having an opening extending therethrough from the flexible member and communicating with the chamber, the flexible 100 member deriving movement from the bobbin and imparting movement to the piston to compress the air in the chamber, the compressed air escaping through the bobbin when sufficient weft is present and being prevented from escaping by contact of the flexible member with the bobbin to actuate the 105 indicating mechanism.

5. In a pneumatic weft detector for the 110 bobbin of a loom, a member movable under influence of the advancing bobbin, means defining an air chamber in which the member moves, said member having a deformable end to engage the bobbin, said member having a passage therethrough connecting the 115 chamber with the air adjacent the bobbin, and indicating mechanism pneumatically connected to the chamber, said member compressing the air in the chamber on all advancing movements of the bobbin, the compressed air escaping to prevent indication of 120 weft exhaustion when sufficient weft is present and being prevented from escape by contact of the flexible member with a substantially denuded bobbin to close the passage 125 in the member to cause indication of weft exhaustion.

6. In a pneumatic weft detector for the 130 bobbin of a loom, movable means to compress air and deriving its movements from

the advancing bobbin each time said means is engaged by an advancing bobbin, a deformable device connected to the means and engaging the bobbin, the air compressed by movement derived from the bobbin as the latter advances escaping through the deformable device and a supply of weft sufficient for continued weaving and being held against escape by the contact of the deformable member with the bobbin when insufficient weft for continued weaving is present, and a device pneumatically connected to said means to indicate weft exhaustion when the compressed air is unable to escape.

7. In a pneumatic weft detector for the bobbin of a loom, a regularly moving actuator, a pneumatically operated controller therefor normally out of the path of the actuator and movable into the path of the actuator when acted upon by compressed air, means defining a chamber pneumatically connected to the controller, a member movable in the chamber to compress the air therein and having an opening therethrough connecting the chamber to the atmosphere, and a deformable element to engage an ad-

vancing bobbin, the advancing bobbin through the deformable element moving the member to compress air in the chamber, the air escaping through the opening in the member when sufficient weft is present, and the deformable element by its contact with a substantially denuded bobbin preventing escape of the compressed air through the opening in the member, thereby causing compressed air to move the controller into operative position with respect to the actuator.

8. In a pneumatic weft detector for the bobbin of a loom, means defining a chamber, a member movable therein to compress air, said chamber normally being open to the atmosphere, deformable means carried by the member to prevent escape of air from the chamber at the time of substantial exhaustion of weft to compress the air in the chamber, and means effective when air is compressed in the chamber to indicate substantial weft exhaustion.

In testimony whereof I have hereunto affixed my signature.

ELBRIDGE R. HOLMES.
